UNITED STATES PATENT OFFICE.

ARTHUR R. MISKIN, OF IDAHO FALLS, IDAHO.

EARTH-SCRAPER.

1,269,484.

Specification of Letters Patent. Patented June 11, 1918.

Application filed October 21, 1915. Serial No. 57,214.

To all whom it may concern:

Be it known that I, ARTHUR R. MISKIN, a citizen of the United States, residing at Idaho Falls, in the county of Bingham and 5 State of Idaho, have invented certain new and useful Improvements in Earth-Scrapers, of which the following is a specification.

My invention relates to earth scraping machines or apparatus such as are used in 10 grading and road construction, particularly to wheeled scrapers, and has for its object to improve the means by which the operations of the scoop are controlled. In the accompanying drawings I have illustrated 15 the preferred embodiment of my invention, referring to which—

Figure 1 is a side elevation of an earth scraping apparatus embodying my invention, the near wheel being removed and the 20 parts held in the positions they occupy normally when the apparatus is moving from place to place but not at work.

Fig. 2 is a plan view of the apparatus.

Fig. 3 is a side elevation of the apparatus, 25 the parts being represented in the positions they occupy when scraping, and loading the scoop.

Fig. 4 is a side elevation of the apparatus representing the scoop completely in inverted position and supported by the runners 30 11.

Fig. 5 represents the parts in the positions occupied when the scoop is discharging its load.

35 The main draft frame of the apparatus consists preferably of the rectangular framework 2 to the front portion of which the draft devices 3 are secured and which is supported above the ground, as by means of the 40 wheels 4 and axle 5 on which the wheels are mounted, the latter being supported in the rear portion of the frame. This is represented as being made of angle iron, suitably braced at its corners, although its specific construction in this respect is not a feature of the invention. The draft frame 2 45 extends forwardly and inclines downwardly from the axle 5, normally occupying about the position indicated in Fig. 1 when the 50 scoop is loaded and the apparatus is being moved from place to place. The scoop of the apparatus is designated 6. It is pivotally supported from the frame 2 by arms 7 secured fast to the scraper and preferably 55 curved as represented in Fig. 2, and have

bearings at their upper ends in brackets or supporting pieces 8 provided therefor and secured to the frame on an intermediate transverse line located preferably about midway between its ends. A pair of runners 11 are secured to the scoop, extending above and in front thereof when the scoop is in position of rest with its bottom 28 resting upon the surface of the ground as represented in Fig. 1. These runners are adapted to hold the scoop above the ground when it is inverted to discharging position. The points of pivotal connection, 27, between the arms 7 and the frame of the machine are at approximately the center of the space 70 bounded by the runners 11 and the rear of the scoop, an arrangement that permits the scoop easily to turn completely over or rotate about pivots 27 as a center, as it will do if left free and the supporting frame is 75 moved forward over the ground. In a machine or apparatus with the parts arranged as described, that is to say, having the supporting frame extending forwardly and inclined downwardly from the main axle, and 80 with the draft attachments secured to its front lower portion, and the scoop supported on an intermediate line between the ends of the frame, under normal conditions the scoop when loaded will not be raised entirely off the surface of the ground when the machine is being moved forward. It 85 will be understood, however, that while the scoop rests upon the surface of the ground when the apparatus is in transit it does so 90 but lightly. Most of the weight is carried by the supporting frame. The draft of the team applied to the frame tends to lift the forward end of the latter and with it the scoop, but the parts of the machine are so related that under normal conditions of use the machine will move forward, under draft, before the scoop is lifted free from the surface of the ground. The contact with the 95 surface of the ground causes the scoop to turn over when free to do so, and advantage is taken of this tendency, as will be later pointed out, without making it necessary that the team be stopped or that the lever of the scoop be changed prior to the 100 beginning of the tilting movements.

12 designates the seat of the machine, and 13, the standard by which it is supported, the latter rising from and being carried by the rear cross piece 14 of the main frame. 110

The latter is preferably separable, being held in place by removable bolts 15, so that when the operator does not care to use the seat the latter and with it the cross piece 14 may be removed.

16 designates a bracket carried by the front cross bar of the frame, to which is pivotally united a link 17. A lever 18, herein called the holding lever, is pivoted 10 at its front end to the link 17 and extends thence rearward to a position conveniently reached by a person occupying the seat 12. The holding lever is provided with a stop piece 19 adapted to engage with a cross bar 15 20-extending between the runners 11, and prevent the scoop from tilting forward and maintaining it in substantially horizontal position, such as indicated in Fig. 1,—the position it normally occupies when the machine is being moved from place to place with the scoop lightly resting on the ground.

The link 17 is extended upwardly beyond the point of its connection, 21, with the holding lever 18, and a rod 22 is pivotally united 25 at its front end with the upper portion of this link, the rod extending thence rearwardly and being pivotally united with a lever 23, herein termed the control lever. This lever is pivotally connected with the 30 holding lever in rear of the stop piece 19, and is provided with a handle in convenient position to be grasped by the occupant of the seat 12. The levers 18 and 23 are adapted to lie side by side, approximately parallel, 35 and the handles by which they are manipulated preferably extend outwardly in opposite directions so that each lever may be conveniently manipulated without interfering with the other.

40 24 designates a latch pivoted to the holding lever 18 and adapted to engage with the cross bar 20 on its rear side, that is, on the side opposite that with which the stop piece 19 engages when the parts are in the position indicated in Fig. 1 thus holding the scoop securely in a substantially horizontal position.

The various positions that the parts of the apparatus may occupy and the manner of 50 operating it may now be stated. In Fig. 1, as has been said, the scoop is represented as being held substantially horizontal,—the position it occupies when being moved from place to place. To maintain it in this position the holding lever is moved downward until the stop 19 comes into engagement with the front edge of the cross bar 20 and the latch 24 is in engagement with the rear thereof. At the same time the control lever 55 60 65 23 occupies its lowermost position, in engagement with the stop 25 carried by the holding lever. This position of the control lever causes the link 17 to assume the inclined position represented, its upper end being carried rearward and its lower end

forward, with the result that the supporting draft frame is moved forward relative to the holding lever, which is now holding the scoop from tilting through its engagement with the runners 11. This relationship of the parts insures that the scoop shall be held with its bottom approximately parallel with the earth surface. If desired the bottom of the scoop may be caused to incline upwardly toward the front when the 70 parts occupy the positions stated, since the link 17 and the parts with which it is connected are constructed so as to permit the desired adjustments by shifting the respective pivotal connections between these parts, 75 as represented in the drawings. I have found it advantageous to arrange the parts so that the scoop is not entirely lifted from the surface of the ground when being moved from place to place as it lessens the labor 80 required in operating the apparatus, causes it to move steadily and smoothly without swaying of the scoop when in transit, and permits the apparatus to be rapidly operated. The moment the team comes to a 85 stop the scoop gently comes to rest upon the surface of the ground without the necessity of the adjustment or manipulation of any parts by the operator. The parts being 90 in the positions shown in Fig. 1, let it be supposed that the scoop is empty and it is desired to fill it with earth. The holding lever remains in its lower position, holding the scoop against freely swinging upon its pivotal supports, while the control lever is 95 swung upward and forward into the position indicated in Fig. 3. This movement of the control lever rocks the link 17, which 100 now becomes a lever, about its pivotal connection 21 as a fulcrum, causing a relative shifting of the positions of the supporting frame and the holding lever, the latter moving forward relatively to the former, and, 105 its connection with the scoop being maintained, the latter is slightly tilted and caused to assume the inclined position indicated in Fig. 3, the front cutting edge 10 being then 110 in engagement with the earth and the bottom 28 of the scoop inclined upwardly and rearwardly; so that a forward movement 115 of the machine as a whole will result in causing the earth to be scraped up and the scoop loaded; and this operation takes place without necessitating the operator giving any attention to the position of the scoop, 120 since that is determined by the levers and associated parts, as has been described. After the scoop is loaded the operating lever is restored to normal position, substantially 125 parallel with the holding lever and in engagement with the stop 25, again bringing the parts to the position indicated in Fig. 1, when the load may be taken to where it is to be discharged. To accomplish a discharge of the scoop, the holding lever 18 is 130

lifted far enough to cause the stop piece 19 to disengage from the cross bar 20. The scoop is now free and rests upon the ground so that a forward movement of the apparatus, as a whole, causes a tilting or rolling over of the scoop from the position represented in Fig. 1 to that indicated in Fig. 5. As the scoop turns over the runners 11 come into contact with the earth, and support the scoop with the edge 10 some distance above the ground surface and its bottom or floor so inclined that the earth contained therein will be discharged. In Fig. 5 I have represented the holding lever as having been lowered,—after having been raised to release the scoop, and the latter having rotated sufficiently far to carry the cross-bar beyond the stop 19,—so that when the rear edge 26 of the scoop comes up under the holding lever it passes the latch 24, which rises to permit this, and is arrested by the stop 19, the parts being then held in the discharging position indicated, which insures a relatively slow discharge of the material scraped up, such as would be employed if it were desired that the material should be deposited in a comparatively thin layer. If a quick discharge is desired the holding lever is not lowered until after the rear edge 26 of the scoop has passed the stop 19, which permits the scoop to turn completely over, as represented in Fig. 4.

With the parts of the apparatus arranged and combined as described not only may the parts be made to assume the several positions illustrated in the drawings, but by judicious manipulation of the holding and control levers an operator may cause them to assume other positions such as the requirements met with in the use of the apparatus may suggest. It is thought, however, that the capabilities of the apparatus have been sufficiently set forth to present the invention. It will be understood that some of the movements of the holding lever carry with it the control lever, as for instance when it is lifted to release the scoop to permit its discharge.

It will be seen that the control lever is a means that operates to shift the fulcrum of the holding lever 18 with reference to the supporting frame, thus causing a changing of the angular relation of the scoop, while it is held, by the lever 18, against freely tilting or swinging in the supporting frame.

The frame 2 is formed of two parts that overlap each other as indicated at 29, where they are securely united by bolts or other means that permit of easy separation. The wheels and cross axle are carried by the rear portion of the frame, while the scoop has pivotal connection with the front part thereof. It is sometimes found desirable to operate the machine without supporting wheels, in which event they and the rear part of

the frame to which they are united are detached from the front part. The machine then becomes a walking scoop, that is, one in which the person operating it walks. If sold without the rear section of the frame, the supporting wheels and driver's seat, the cost of the machine is materially reduced.

What I claim is:—

1. In an earth scraper, the combination with ground wheels, of a draft frame pivotally supported at its rear by the ground wheels, its forward end being freely movable vertically, draft connections at the said forward end of the frame, a scoop pivotally supported directly by the said frame and arranged under working conditions to rest upon the ground, an adjustable holding lever pivoted to the draft frame and arranged to be connected with the scoop for positively holding the latter, and means for adjusting and maintaining the holding lever so that the scoop while in contact with the ground, is either in an inclined position for loading or in an approximately horizontal position for transit accordingly as the holding lever is adjusted, the said lever being arranged to be disconnected from the scoop at will, leaving it free to be turned over by reason of its contact with the ground, when the scraper as a whole is moved forward.

2. In an earth scraper, the combination with ground wheels, of a draft frame supported by the wheels, a scoop pivotally supported by the frame and adjustable means pivotally united with the frame at a point distant from the line of the pivot of the scoop, the means being adapted to be connected with the scoop and arranged to positively hold the latter, while in contact with the ground, either in an inclined position for loading or in an approximately horizontal position for transit, accordingly as the means are adjusted, the said means being arranged to be disconnected from the scoop at will leaving it free to be turned over by reason of its contact with the ground when the scraper as a whole is moved forward.

3. In an earth scraper, the combination of a wheel-supported draft frame, a scoop pivotally mounted in the frame and adapted to rest upon the ground whereby as the scraper as a whole is drawn forward the scoop is tilted to discharging position, a lever supported by the frame and adapted to hold the scoop against freely tilting, and means for shifting the lever and its fulcrum bodily relative to the frame while it is holding the scoop, whereby the angular position of the scoop is changed while being held from freely tilting.

4. In an earth scraper, the combination of a supporting draft frame, a scoop suspended therein so as to be free to be tilted to discharging position, a lever pivotally supported by the draft frame and adapted

to hold the scoop against tilting with its bottom substantially parallel with the surface of the ground, or to release the scoop permitting it to tilt to discharge, accordingly as the lever is adjusted, and a control lever for shifting the relations of the fulcrum of the said lever to the draft frame at will, whereby the scoop may be moved to scraping position while held against free-dom to tilt.

5. In an earth scraper, the combination of a supporting draft frame, a scoop suspended therein so as when free it may be tilted to discharging position, a link pivotally supported near one end by the main frame, a lever pivotally connected with the said link between its ends, and adapted to hold the scoop against tilting, a control lever pivoted to the said holding lever, and a link 15 uniting the control lever with that end of the link to which the holding lever is pivoted which is opposite the end connected with the supporting frame, whereby by the adjustment of the control lever the fulcrum 20 of the holding lever is shifted relative to the frame and the angular position of the scoop is changed while held against free-tilting.

6. In an earth scraper, the combination 25 of a supporting frame, a scoop suspended therein so as to be free to tilt to discharging position when left free, a pair of runners carried by the scoop and extending upward therefrom, and by which the scoop may be supported when inverted, a lever mounted on a fulcrum carried by the supporting frame, interengaging parts between the said runners and the holding lever whereby when the latter is moved into one position the 30 scoop is held against freely tilting, and when moved to another position disengagement takes place and the scoop is left free to tilt, and means for shifting the fulcrum of the said holding lever with reference to 35 the supporting frame whereby the angular position of the scoop may be changed while it is held against freely tilting.

7. In an earth scraper, the combination 40 of a supporting frame, a scoop pivotally mounted in the frame and arranged to be suspended therein with its center of gravity below the frame, a runner secured to the scoop and extending above it, the scoop being adapted to turn over and be supported 45 by the said runner for discharging its contents, and adjustable means supported by the frame and arranged to be brought into connection with the said runner for positively holding the scoop against tilting, or 50 to be disconnected from the said runner to

release the scoop and permit it to tilt for discharging.

8. In an earth scraper, the combination of a supporting frame, a scoop pivotally mounted in the frame and arranged to be suspended therein with its center of gravity below the frame, a runner secured to the scoop and extending above it, the scoop being adapted to turn over and be supported by the said runner for discharging its contents, adjustable means supported by the frame and arranged to be brought into connection with the said runner for positively holding the scoop against tilting, or to be disconnected from the said runner to release the scoop and permit it to tilt for discharging, and means for shifting the said holding means while in holding connection with the said runner, whereby the angular position of the scoop in the frame is changed while it is held against freely tilting.

9. In an earth scraper, the combination of a supporting frame, a scoop pivotally mounted in the frame and arranged to be suspended therein with its center of gravity below the frame, a pair of runners secured to the scoop and extending above it, a cross-bar uniting the runners, and means for holding the scoop against freely turning on its pivots, supported in the frame and arranged to engage with the cross-bar uniting the said runners.

10. In an earth scraper, the combination of a supporting frame, a scoop pivotally suspended therein so as to be free to turn over so as to discharge its contents, the scoop being located so as, under conditions of loading and transit, to rest upon the surface of the ground, draft devices connected with the frame in front of and below the pivotal point of suspension of the scoop, wheels for supporting the frame connected therewith in rear of and above the pivotal points of support of the scoop, and means for holding at will, the scoop rigidly in working position and against tilting.

11. In an earth scraper, the combination of a rigid supporting frame formed of two separable portions securely united, a cross axle upon which are supporting wheels, secured to the rear separable portion of the said frame, a scoop pivotally supported in the front portion of the said frame, means supported by the forward portion of the frame arranged to hold the scoop against turning on its pivots and to control its movements and angular relations while working, and draft devices connected with the forward portion of the frame.

ARTHUR R. MISKIN.
